UNITED STATES PATENT OFFICE.

HAROLD P. DONLE, OF MERIDEN, CONNECTICUT, ASSIGNOR TO THE CONNECTICUT TELEPHONE & ELECTRIC COMPANY, INCORPORATED, OF MERIDEN, CONNECTICUT, A CORPORATION OF CONNECTICUT.

METHOD AND APPARATUS FOR INCREASING ELECTRONIC EMISSION.

Application filed May 9, 1919, Serial No. 295,897. Renewed August 16, 1923.

To all whom it may concern:

Be it known that I, HAROLD P. DONLE, a citizen of the United States of America, residing at Meriden, Connecticut, have invented new and useful Methods and Apparatus for Increasing Electronic Emission, of which the following is a specification.

The object of my present invention is to increase the electronic emission of a hot electrode or filamentary cathode.

I have discovered that when a material having a high temperature coefficient of resistivity, such as glass, is subjected to the action of electrolysis between two electrodes, the electronic emissivity of the cathode, as the result of this treatment, is greatly increased.

It appears that some of the elements or material emitted during such disassociation are deposited on, or carried to, the filament cathode element and become a source of electronic emission, the actual cathode or filament being the support for this electronic source.

This material which is deposited upon and retained at the filament cathode element is of such a nature that its emission at a given temperature is much greater than that of the supporting filament or cathode material, which may be of a metal such as tungsten, molybdenum, etc.

For the sake of a more complete disclosure attention is directed to the accompanying drawing wherein, I have illustrated first a test form of apparatus and secondly, a commercial development of the invention.

More specifically, Figs. 1, 2 and 3 illustrate a testing or demonstrating form of the tube, showing the connections for demonstrating the operation of the invention.

Fig. 4, is a graphic illustration of the results of such tests.

Fig. 5, is a more or less diagrammatic illustration of a commercial use of the invention.

The tube 7 illustrated in Figs. 1, 2 and 3, is shown provided with a neck 8 by which it is connected with a vacuum pump, the latter not being illustrated. It will be understood however, that any efficient form of high vacuum pump may be employed.

Within the tube are sealed the hot electrode, which in this case is a metallic fila-

ment 9 and an electrode 10 in the form of a coil surrounding the filament.

On the outside of the tube there is provided an external electrode 11 which may be in the form of a coating of silver, or the like, applied directly to the glass wall of the tube.

In the first test the filament was heated by a battery A, one side of which was connected with a variable source of potential B, the other terminal of this potential being connected in series with a micro-ammeter 12 to the electrode 10; which in this case acts as the anode. The anode potential was varied in steps by means of the adjustable resistance shunt 13 and readings of the anode current taken for different values of anode potential, the results of these observations being plotted and indicated by the curve 14 in Fig. 4. It will be seen that saturation occurred at approximately 5 volts with an anode current of 100 micro-amperes.

The next step consisted in disconnecting the inside anode 10 from circuit and connecting the second battery B with the external electrode 11 by means of a connection 15. By these connections the external electrode is made an anode and an electron discharge is created between the filament and outside anode through the wall of the glass. This circuit was allowed to operate for about five minutes. During this time I believe the

action was that the passage of current from battery B to electrode 11, through the warmed glass wall 7 and across the evacuated space to the filament 9, set up an electrolytic dissociation of the glass and projected into the space within the tube a quantity of positive sodium ions derived from the glass.

Some of these were deposited upon the cooler non-conducting portions of the tube and some were attracted by the negative potential of the cathode or filament and deposited thereon. The former deposit in the form of a bright metallic film is then observed on the inner wall and in the end portion of the tube as indicated at 16. This film has the appearance and exhibits the characteristics of metallic sodium and so far as I have been able to ascertain up to the present time is in fact sodium in the metallic form. In the course of this action a certain amount of material is carried to and deposited upon the filamentary electrode or cathode 9, as

is further demonstrated from the step which follows and will now be described.

In the third step of the test the outside anode is disconnected and the original connections restored, as indicated in Fig. 3. With these connections the anode potential is varied in the same way as in making the first part of the test and the results plotted as before. The values obtained are indicated by the curve 17 in Fig. 4. This curve shows that the emission from the filament is very greatly increased and that at the same time the saturation voltage is increased. The anode current at saturation is shown 10 to be 2400 micro-amperes. In other words, the electronic emission, as a result of the electronic discharge, has been increased in the ratio of twenty to one.

During all three steps of this test the 20 vacuum pump was connected with the tube and was operated to maintain the highest possible vacuum within the tube and to remove any gases that might exist. This removal of whatever gases that may have 25 existed within the tube, did not however affect the deposit of the metallic element within the tube.

From tests which I have conducted it 30 appears that the increased emission is not permanent. Usually the increased emission will last for approximately ten minutes at the end of which time the emission rate will fall until it drops back to the rate which is normal for the metal which is employed, in 35 other words, that rate represented for instance by the first curve (14).

The increased electronic emission may 40 however be maintained by continuously passing current through the wall of the glass tube during the normal operation of the tube. Thus, as I understand it, renewing the deposit upon the filamentary cathode by the continuous or substantially continuous electrolytic dissociation of the current-carrying glass and the consequent provision of 45 sodium ions for this purpose.

In Fig. 5 I have illustrated a form of apparatus and shown a completed tube wherein this result is accomplished. In this 50 illustration there is in addition to the filament and the anode within the tube, a controlling electrode or so-called grid 18, the grid and anode each consisting in this case of an open spiral of wire surrounding the 55 filament, the grid being disposed within the anode and between that and the filament. An external electrode or secondary anode 22, similar to that first described, is provided, the same being shown as a band of silver, or 60 other metal of like characteristics, applied directly to the outer wall of the bulb. The three elements of the tube are shown connected in the usual way for detecting radio oscillations, the control electrode 18 being 65 shown connected with the antenna 19 and

the anode 10 being shown connected in the telephone circuit 20. The outside electrode 22, which is provided in this instance simply for the purpose of increasing and holding constant the electron flow, is shown connected through a choke-coil 21 with the positive terminal of the B battery. This choke-coil is shown provided with an iron core so as to choke back electrical oscillations and the resistance of the coil is such as to allow 70 a part of the energy of B battery to pass through the glass. As described above, this passage of current through the glass, as I understand it, results in slight electrolytic dissociation of the glass wall and consequently 75 the liberation of some of the positive sodium ions and the formation of a deposit upon the filament or cathode which increases its electronic emission. This construction thus provides a means for producing and 80 maintaining a greatly increased electronic emission and hence a more efficient instrument.

While I have described the somewhat obscure phenomena observed within these vacuum tubes in terms of electrolytic dissociation 85 of the glass to produce a quantity of positive sodium ions which are attracted to the filamentary cathode and deposited thereon, and while this explanation is in full agreement with all the facts I have been able to determine in long study of these actions, I do not wish to be bound by this particular theory. My discovery is eminently practical and is not limited in its useful applications by the theoretical analysis which I 90 have attempted in the interest of clarity; I have found that by the process described I can increase many-fold the electron-emitting ability of a cathode, without in any way exposing it to the action of special minerals, etc., and without treating it (or mixing with it) prior to its mounting within the vacuum tube any materials not usual in filament manufacture. My invention therefore permits me to secure greatly increased electron 95 emission at any temperature from a standard cathode or filament of tungsten, molybdenum or the like, and consequently to secure the full equivalent of normal electron emission from such filaments at temperatures far below normal.

The form of construction illustrated in Figs. 1 to 3 in which there is an unobstructed electron path between the cathode 9 and the anode 10 is claimed in my application No. 616,660 filed February 3rd, 1923. In said application I have also broadly claimed with respect to vacuum tube signalling devices the use of metals such as sodium which can be derived from the wall of the tube for the purpose of increasing the electron emission of a highly refractory filamentary cathode.

I claim:

1. The method of increasing the elec- 100

tronic emission from the cathode of a thermionic valve which consists in extracting from the material of the walls of said valve a material having a higher electronic 5 emission than the material of which the cathode is composed and depositing the same upon the cathode.

2. The method of increasing the electronic emission from the cathode of a thermionic 10 valve which consists in depositing one of the products of electrolytic decomposition of the material of the tube upon said cathode.

3. The method of increasing electronic emission of an electrode within a vacuum 15 tube which comprises electrolyzing a body of glass-like material and supplying products of said electrolytic decomposition to said electrode while the tube is in operation.

4. The method of increasing electronic 20 emission of an electrode within a vacuum tube which comprises electrolyzing a body of glass-like material and continuously supplying products of said electrolytic decomposition to said electrode.

25 5. The method of increasing electronic emission of a cathode within a vacuum tube which comprises electrolyzing a body of glass-like material and supplying products of said electrolytic decomposition to said cathode while the tube is in operation.

6. A step in the method of increasing the electronic emission from an electrode within the bulb of a thermionic valve, which consists in extracting an emission-increasing 35 material from the material of the wall of said bulb.

7. The method of increasing the electronic emission from the electrode of a thermionic valve having a tube with a wall, 40 which consists in exhausting the tube of said valve and depositing within the tube an emission-increasing material derived from the material of the wall of said tube during said exhausting process and prior to the 45 sealing of the tube.

8. The process of operating a thermionic valve, which comprises passing a thermionic stream between a filament and an anode disposed within the tube and increasing the filament emission by passing a thermionic current between the filament and an electrode disposed at the outer surface of the tube.

9. The process of operating a thermionic 55 valve, which comprises controlling the thermionic current between a filament and an anode disposed within the tube by a control element in the tube and interposed between the filament and inside anode, and increasing the filament emission by passing a thermionic current through the wall of the tube and between the filament inside the tube and an electrode disposed at the outer surface of the tube.

60 10. The method of increasing the elec-

tronic emission from an electrode within the glass bulb of a thermionic valve which consists in extracting a metallic element from the material of said glass bulb and depositing the same upon the electrode aforesaid. 70

11. The method of increasing the electronic emission from an electrode within the glass bulb of a thermionic valve which consists in extracting a metallic element from the material of said glass bulb and 75 depositing the same within the bulb.

12. A thermionic valve comprising a tube, an electrode within said tube and means for renewing a deposit on said electrode of a metal derived from the material 80 of the wall of said tube having a greater rate of electronic emission than the material of said electrode.

13. In apparatus of the character described, a tube, a cathode within said tube 85 and means for extracting an element from the material of the tube and supplying the same to said cathode.

14. In a thermionic valve, an evacuated tube, a filament, an anode and a control 90 electrode all sealed within the tube and means for increasing the electronic emission of said filament, said means comprising an external emission-increasing electrode on the outer surface of said tube. 95

15. In an electrical oscillation device, an evacuated tube, a filament, an anode and a control electrode all sealed within the tube, an external electrode on the outer surface of said tube and means for preventing flow of high frequency oscillations to said external anode. 100

16. In a thermionic valve, an evacuated tube, a filament and an anode sealed within said tube and means for increasing the 105 electronic emission of said filament, said means comprising an external emission-increasing anode at the outer surface of the tube.

17. In a thermionic valve, an evacuated tube, a filament and an anode sealed within the tube, means for increasing the electronic emission of said filament, said means comprising an external emission-increasing electrode at the outer surface of the tube, 115 a source of potential connected with the filament and with said external electrode and a choke-coil interposed in said connections to said external electrode.

18. In an electrical oscillation device, an 120 evacuated tube, a filament and an anode sealed within the tube, an external electrode at the outer surface of the tube, a source of potential connected with the filament and with said external electrode and means for 125 preventing flow of electrical oscillations to said external electrode.

19. A three electrode tube having a highly 120 refractory filamentary cathode, an anode, a third electrode and alkali metal under con-

- ditions to permit its ionization when in operation.
20. The process of operating a thermionic valve which consists in passing a thermionic current between a filament and an anode located within the tube of said valve and simultaneously passing a thermionic current through the wall of said tube and between the filament within the tube and a secondary anode at the outer surface of the tube.
21. The process of operating a thermionic valve which consists in passing a thermionic current between a metallic filament and an anode located within the tube of said valve and simultaneously passing a thermionic current through the wall of said tube and between the metallic filament within the tube and a secondary anode at the outer surface of the tube.
22. An evacuated electron-tube containing a highly refractory filamentary cathode, an anode, an auxiliary electrode, and a supply of an alkali metal within said tube.
23. An evacuated electron-tube containing a highly refractory filamentary cathode having a coating of an alkali metal, an anode and an auxiliary electrode arranged to modify the field between said cathode and anode.
24. A vacuum tube having a cathode, an anode, and a third electrode and containing free sodium.
25. A vacuum tube having a cathode, an anode, and a third electrode and containing a free alkali metal.
26. A vacuum tube having a cathode, an anode, a third electrode, and means for supplying sodium ions within the tube.
27. A vacuum tube having a cathode, an anode, a third electrode, and means for supplying ions of an alkali metal within the tube.
28. A vacuum tube device for electric signalling having an anode, a highly refractory filamentary cathode coated with an alkali metal, means for maintaining such coating during operation of the tube and an auxiliary input electrode.
29. A vacuum tube device having a highly refractory filamentary cathode coated with an alkali metal, an anode, an auxiliary electrode, a coating of an alkali metal on the inner wall of the tube, and means for renewing the coating on the cathode during operation of the tube.
30. In a radio signalling system, a wave intercepting device, a vacuum tube operatively connected therewith and having a highly refractory filamentary cathode, an anode and a third electrode, said tube containing free alkali metal, and a translating device operatively connected with said tube.
31. In a radio signalling tube, a highly refractory filamentary cathode of a single commercially pure metal, an anode, a third electrode, free alkali metal within said tube, and means for maintaining a coating of said alkali metal on said filament.
32. A radio signalling system, a wave intercepting device, a vacuum tube operatively connected therewith and having a highly refractory filamentary cathode of a single metal, an anode, a third electrode, means for continuously supplying an alkali metal to said cathode and a translating device operatively connected with electrodes of said tube.

HAROLD P. DONLE.
